UNITED STATES PATENT OFFICE.

ALBERT BODDEKER, OF CHICAGO, ILLINOIS.

OIL BURNER.

Application filed April 9, 1926. Serial No. 100,905.

My objects, generally stated, are to provide for the more nearly complete gasification of the oil, thereby attaining greater heating efficiency of the fuel and producing a cleaner and more effective flame with the elimination of the production of free carbon; to provide a novel, simple and inexpensive construction for accomplishing these results, more especially in a natural-draft burner; to provide for the supporting of the burner in the position necessary to be occupied for accomplishing the most effective results; and other objects as will be manifest from the following description.

Referring to the accompanying drawings:—

Figure 1 is a view in side elevation of my improved burner, illustrating it as installed in a furnace shown in sectional elevation. Figure 2 is a plan view thereof. Figure 3 is a view in sectional elevation of the burner, the section being taken at the line 3—3 on Fig. 2 and viewed in the direction of the arrows. Figure 4 is a broken section taken at the line 4—4 on Fig. 3 and viewed in the direction of the arrows; and Figure 5, a broken sectional view taken at the line 5 on Fig. 2 and viewed in the direction of the arrow.

The burner, in accordance with the preferred illustrated embodiment of my invention, comprises a base portion 10 and a superposed manifold portion 11 shown as supported thereon, the base portion 10 being formed at its center with an inverted bell portion 12 presenting a receptacle 12^a and containing at opposite ends thereof apertures 13 surrounded by continuous flanges 14 shouldered, as represented at 15, and forming seats for a purpose hereinafter described. The bell portion 12 at the center of the receptacle 12^a contains a screw-threaded opening 16 in which a pipe 17 is screwed to project upwardly and downwardly at its opposite ends beyond the portion 12, the side wall of the pipe 17 where it extends above the base of the portion 12 being apertured, as represented at 18. Surmounting the pipe 17 and vertically spaced from the portion 12 is a burner-head in the form of a generator plate 19 preferably of the circular stepped form, as shown, with the upper surface of each annular step portion annularly grooved, as represented at 20. The plate 19, which is preferably fastened to the burner-section 10,

as by screws 19^a, engaging pairs 19^b of ears 19^c on the plate 19 and screwing into the openings in diametrically-opposed lugs 10^b formed on the walls of the receptacle 12^a, is centrally apertured, as represented at 21, into which the open upper end of an oil-pipe 22 is screwed, the oil to be gasified being supplied to the upper surface of the plate 19 through this pipe which latter extends downwardly through the pipe 17, and in spaced relation thereto, as shown.

The pipe 17 is screwed at its lower end into the opening 23 of a cross-fitting 24, the lower opening 25 in which has screwed into it a threaded pipe-section 26 which latter is screwed at its lower end into an opening 27 in a T-fitting 28 screwed at an opening 30 therein on the upper end of a pipe 29 supported as hereinafter described.

The manifold section 11 is of general inverted U-shape and seats at its inlet end portions 31 and 32 upon the seats 14 of the base member 10, the section 11 containing between its ends a tubular downwardly-projecting outlet portion 33 communicating with the interior of the manifold, and arranged concentric with the generator plate 19 and in vertically spaced relation thereto. It may be here stated that the purpose of the manifold section 11 in so far as it has been described, is to conduct air, as for example air drawn into it by the natural draft of the furnace in which the burner is located, upwardly against surfaces which are heated by the burning of the fuel, and thence downwardly against the generator plate 19 for mixture with the oil supplied to this plate, it being preferred that the inner surfaces of the manifold section 11 be provided with a series of substantially parallel fins 34 and 35 to enhance the heating effect on the air and reinforce the manifold to ensure that it presents the desired durability.

The burner also comprises a pair of pipes 36 and 37 which are screwed at their lower horizontally disposed ends into threaded openings 38 and 39 in the cross-coupler 24. The pipes 36 and 37 include inverted U-shape pipe-sections 40 and 41 shown as extending above the base section 10 at opposite sides of the manifold section 11, with their ends projecting downwardly through openings in the corner-portions of the base member 10, the downwardly extending leg portions 42 and 43 of the pipe sections 40

and 41 being open to form downwardly opening inlets located at diagonally opposed corners of the base member 10.

The purpose of the conduits 36 and 37 is to direct air supplied thereto, as by the natural draft through the furnace equipped with the burner, through courses so disposed that the air is heated and thereupon, according to the preferred illustrated embodiment 10 of my invention, conducted into and through the fitting 24 and pipe 17 and thence into the space below and surrounding the generator plate 19, for heating the oil as it flows upwardly through the pipe 22 and furnishing 15 a supply of heated air below and around the burner head and supplementary to that supplied thereto from above through the manifold 11.

The oil pipe 22 which extends at its upper 20 end through the coupler 24 and pipe 17 as stated, is shown as having a substantially horizontally disposed portion 22^a which projects through the opening 44 of the T-coupler 28 in spaced relation to the walls 25 of this opening, the coupler 28 being connected with a drain pipe 45 screwed into the opening 44 and through which the portion 22^a of the pipe extends in spaced relation to the latter. The upper end of the 30 pipe 29 is closed, as for example by a plug 46, whereby should oil overflow from the plate 19, as for example in case of extinguishment of the flame and the continuing 35 of the supplying of oil to the plate, it will drain through the openings 18 into the pipe 17 and thence out through the pipe 45. The apparatus is preferably provided with drip-bucket-controlled mechanism operating automatically in the event of overflow through 40 the pipe 45, to shut off the supply of oil to the burner. Such a mechanism, which is well known in the art and therefore need not be detailed, is diagrammatically illustrated in Fig. 1 in which the bucket for receiving 45 the oil is represented at 46 and is shown as hung on a trip lever 47 controlling a shut-off valve located at the portion 48 of the pipe section 22^a and controlling the flow of oil to the generator plate.

50 The burner structure illustrated also comprises a supporting base 49 having an upwardly extending socket portion 50 into which the lower end of the pipe 29 extends and to which it is secured, to permit of its 55 vertical adjustment, by set screws 51. The base 49 at which the burner is supported in operative position, is provided with vertically adjustable legs shown as screws 52 arranged in triangular form at which the 60 structure rests upon the floor. By providing these adjustable legs the burner structure may be caused to extend in vertical position, with its generator plate 19 horizontal, regardless of unevenness of the floor.

65 The burner structure may be installed in a

furnace in any desirable way. In the arrangement shown the burner structure, which is located centrally of the side wall 53 of the furnace, rests at the screws 52 upon the floor represented at 54 and upon which 70 the furnace is supported. The annular space between the base member 10 of the burner and the side wall of the furnace may be filled in with any suitable material, as for example fire clay or cement composition represented at 55 and confined in a trough-shaped annular receptacle 57 located in this space and supported, as for example by brackets 58 secured to the side walls of the furnace pit.

In the particular installation, the natural draft through the furnace, created by the draft through the stack, causes air to pass upwardly through the inlet ends of the manifold and discharge downwardly through 80 its outlet 33 against the generator plate 19 to which the oil is supplied. The draft referred to also causes air to enter the depending inlets 42 and 43 of the pipes 36 and 37 which discharge into the space below and around 85 the generator plate 19. As the manifold and air conducting pipes referred to are subjected to the heat generated by the burning fuel, the air flowing through the courses thus provided, becomes highly heated and in such 90 heated condition is supplied to the oil at the generator plate 19 thereby augmenting the gasification of the fuel, preventing the production of free carbon and causing a 95 clean and intense flame to be produced. Furthermore by positioning the oil pipe 22 as shown and described, it is subjected to the heated air flowing through the pipe 17, and thus the oil is more readily gasified at the 100 plate, with the manifest advantage.

105 The feature of providing the adjustable legs 52 for the burner structure, is of advantage, especially in the type of burner shown and described and involving a generator plate over which the oil, to be burned, flows, inasmuch as it is essential for the most effective operation of the burner that this plate extend horizontally, to ensure an even distribution of the oil over it, and such positioning of the plate may be effected in applicant's apparatus, regardless of unevennesses existing in the floor upon which the burner is supported.

110 The feature of connecting the drain pipe 45 with the pipe through which heated air is introduced into the burner structure and providing this pipe with the openings 18, is of advantage inasmuch as such air as may enter the burner through the drain pipe 45 becomes mingled with the heated air supplied through the pipes 36 and 37 and is thus 115 tempered.

120 While I have illustrated and described a particular construction embodying my invention, I do not wish to be understood as 125

intending to limit it thereto, as the same may be variously modified and altered without departing from the spirit of my invention.

5. What I claim as new, and desire to secure by Letters Patent, is:

1. In an oil burner, in combination, a burner head, means for delivering oil to said burner head, a preheating chamber surrounding said delivery means, means for delivering heated air above the burner head, and means for delivering heated air to said preheating chamber comprising a member having an air intake below the plane of the burner head, a portion extending over the burner head in the path of the flames and a non-perforated delivery connected with said preheating chamber.

2. In an oil burner, in combination, a burner head, means for delivering oil to said burner head, a preheating chamber surrounding said delivery means, an overflow pipe connected with said preheating chamber and surrounding said delivery means, means for delivering heated air above the burner head, and means for delivering heated air to said preheating chamber comprising a member having an air intake below the plane of the burner head, a portion extending over the burner head in the path of the flames and a non-perforated delivery connected with said preheating chamber.

3. In an oil burner, in combination, a mounting plate, a burner head mounted above said plate, means for delivering oil to said burner head, a preheating chamber mounted below said plate and surrounding said delivery means, a manifold extending over the burner head mounted on said plate and provided with a delivery port directly over the burner head, and means for delivering heated air to said preheating chamber comprising a member mounted on said plate parallel to said manifold and provided with an air intake below said plate and a non-perforated delivery connected with said preheating chamber.

4. An oil burner, in combination, a mounting plate, a burner head mounted above said plate, means for delivering oil to said burner head, a preheating chamber mounted below said plate and surrounding said delivering

means, a manifold extending over the burner head mounted on said plate and provided with a delivery port directly over the burner, and means for delivering heated air to said preheating chamber comprising members mounted on said plate parallel to said manifold and each provided with an air intake below said plate and a non-perforated delivery connected with said preheating chamber.

5. In an oil burner, in combination, a mounting plate provided with openings at the center, at each corner, and at each end midway the width, a burner head mounted above said central opening, a preheating chamber mounted below said central opening, means for delivering oil to said burner head, extending through said central opening and said preheating chamber, a manifold having a delivery port over said burner head mounted over said openings midway the ends of the plate, and means for delivering heated air to said preheating chamber comprising members mounted on said plate parallel to said manifold, each member having an air intake extending through one of said corner openings and a delivery connected with said preheating chamber extending through another of the corner openings of said plate.

6. In an oil burner, in combination, a mounting plate provided with openings at the center, at each corner, and at each end midway the width, a burner head mounted above said central opening, a preheating chamber mounted below said central opening, means for delivering oil to said burner head extending through said central openings and said preheating chamber, a manifold having a delivery port over said burner head mounted over said openings midway the ends of the plate, and means for delivering heated air to said preheating chamber comprising members mounted on said plate parallel to said manifold, each member having an air intake extending through one of said corner openings and a delivery extending through the other corner opening that is located on the same side of the manifold and connected with the preheating chamber.

ALBERT BODDEKER.
